US0D1108142S

(12) United States Design Patent (10) Patent No.: US D1,108,142 S
(45) Date of Patent:  Jan. 6, 2026

(54) HANDBAG

(71) Applicant: BOTTEGA VENETA S.R.L.,
Montebello Vincentino (IT)

(72) Inventor: Matthieu Blazy, Milan (IT)

(73) Assignee: BOTTEGA VENETA S.R.L.,
Montebello Vicentino (IT)

() Term: 15 Years

(21) Appl. No.: 29/970,142

(22) Filed: Oct. 25, 2024

(30) Foreign Application Priority Data

Apr. 30, 2024 (EM) 015059382-0009

(51) LOC (15) Cl. 03-01

(52) U.S. Cl.
USPC D3/244

(58) Field of Classification Search

USPC D3/232–234, 238, 243–246
CPC .. A45C 3/06; A45C 3/00; A45C 13/02; A45C
13/1046; A45C 13/08; A45C 3/001

See application file for complete search history.
